INVENTOR.

George L. Cady.

United States Patent Office.

GEORGE L. CADY, OF LOWELL, MASSACHUSETTS.

Letters Patent No. 98,026, dated December 21, 1869.

IMPROVEMENT IN SAP-SPOUTS.

The Schedule referred to in these Letters Patent and making part of the same.

To all whom it may concern:

Be it known that I, GEORGE L. CADY, of Lowell, in the county of Middlesex, and State of Massachusetts, have invented new and useful Improvements in a Combination Sap-Spout and Bucket-Hanger; and I do hereby declare that the following is a full and exact description thereof, reference being had to the accompanying drawings, and to the letters of reference marked thereon.

My invention consists in the arrangement and construction of the sap-spout, in combination with the bucket-hanger, whereby the spout is held in position by the weight of the bucket, with contents, without mutilating or contracting the fibres of the wood in the least, thus allowing the sap to flow freely; being simple, cheap, durable, and useful.

To enable others skilled in the art to make and use my invention, I will proceed to describe its construction and operation.

Figure 1 represents a longitudinal section of my improved device, showing its application and operation.

Figure 2 represents a plan of my improved device.

Figure 3 represents a side elevation of the same, with a fixed hanger.

Figure 4 represents a similar elevation as fig. 3, with movable hanger.

Similar letters in the different figures indicate corresponding parts.

In the construction of my improved device, *a* represents the spout, its form being semicircular, of the required length and taper, the nose *b* of which is provided with a lip, *c*, the other end being inclined in the reverse direction from the lip *c*, on the end of which is formed a spur, *d*.

This inclined end is concave in form, through the bottom of which an opening, *e*, is made, which leaves a free passage for the sap to flow from the tree *h* to and through the entire length of the spout *a*.

Located and cast on or secured to the spout *a*, on its under side, between the nose *b* and spur *d*, is the fixed hanger *f*, as shown in figs. 1 and 3, although the same results would be obtained provided the hanger *f* was movable, as shown in fig. 4 of the drawings.

The device, when thus constructed, is galvanized or plated with tin, or any other metal or material which will prevent the same from rusting, it then being ready for use.

In the common sap-spoouts and bucket-hangers now in use, their construction and arrangement being such renders them not only inconvenient to be used, but, when driven into the tree, the fangs wedge up and contract the fibres, which not only injures the tree, but impedes the flow of sap from the same; and also when it is required to remove them from the tree, they being driven into the same so firmly, makes it extremely difficult, without breaking them or damaging the tree to a greater or lesser extent.

With the use of my improved device, these difficulties are to a great extent obviated. The inclined part of the spout *a* is inserted into the hole *g*, previously prepared, the nose *b* inclining upward. It is then slightly driven into the hole *g*, so that the end of the spout *a* rests on the fibres of the tree *h*.

The nose *b* is then pressed downward, which operation forces the spur *d* into the top part of the hole *g*, this spur *d* being the only point in the device that mutilates the fibres in the least.

The bucket is then hung to the hanger *f*, which, by its weight, keeps the spout *a* in position, at the same time perfectly packing the spout *a* where it comes in contact with the tree *h*.

This inclined part being concaved, prevents the escape of sap from the tree *h*, and conducts the same to the spout *a*, where it runs toward the nose *b*. By its inclining downward, and by aid of the lip *c*, it is compelled to drop from the same into the bucket; and when it is desired to remove the spout *a* from the tree *h*, the nose *b* is inclined upward, which removes the spur *d* from the fibres. It then can be easily and quickly removed.

In some instances it may be desirable to have hangers of different lengths. When it is thus required, I provide a movable hanger, *f*, as shown in fig. 4 of the drawings, the spout *a* in either case being held in position by the weight of the bucket, with contents.

Having thus described my invention,

What I claim, and desire to secure by Letters Patent, is—

The combination of the spout *a*, spur *d*, and hanger *f*, constructed and arranged to operate together substantially as and for the purpose herein specified.

GEORGE L. CADY.
